REFRIGERATED CASE WITH REPLACEABLE
COMPLETE REFRIGERATED UNIT

Joseph John Schmidt and Louis L. Popky, Wilkes-Barre, Pa., assignors to Fleetwood Airflow Inc., Wilkes-Barre, Pa., a corporation of Pennsylvania

Application March 4, 1948, Serial No. 12,958

6 Claims. (Cl. 62—102)

1

This invention appertains to novel and useful improvements in devices especially designed for maintaining certain articles cool.

An object of this invention is to refrigerate a compartment wherein devices, articles of food, drink and the like may be maintained at a pre-selected temperature.

Another object of this invention is to cool the compartment by improved circulation within a housing.

A still further object of this invention is to detachably support a cooling means within a housing, whereby the entire unit for cooling the interior of the housing may be easily and readily detached and removed.

A still further object of this invention is to humidify the interior of the housing by improved means.

Another object of this invention is to detachably support a compressor, motor therefore and cooling unit so that it may be readily attached and detached and to so design this unit that it may be utilized in association with many types of coolers, refrigerators and the like.

Ancillary objects and features of novelty will become apparent to those skilled in the art, in following the description of the preferred forms of the invention, illustrated in the accompanying drawings, wherein:

Figure 1 is a sectional view of one form of the invention;

Figure 2 is a sectional view taken on the line 2—2 of Figure 1 and in the direction of the arrows;

Figure 3 is a sectional view taken substantially on the line 3—3 in Figure 1 and in the direction of the arrows;

Figure 4 is a sectional view taken substantially on the line 4—4 in Figure 1;

Figure 5 is a perspective view of the humidifying means forming a part of the present invention;

Figure 6 is an enlarged sectional detail of construction, taken substantially on the line 6—6 in Figure 5 and in the direction of the arrows;

Figure 7 is an enlarged sectional view illustrating a modified form of the invention;

Figure 8 is a sectional view taken substantially on the line 8—8 in Figure 7 and in the direction of the arrows;

Figure 9 is a sectional view taken substantially on the line 9—9 of Figure 1 and in the direction of the arrows;

Figure 10 is a perspective view illustrating a

detail of a position utilized in association with the invention, and;

Figure 11 is an enlarged perspective detail of construction showing a portion of the absorbent material and means for support therefore.

This invention has been developed to provide a device whereby the articles to be maintained in a cool condition may be properly humidified by extremely inexpensive means. It is another prime purpose of the present invention to provide improved circulation and air flow within the housing, whereby direct impinging of the flowing air will not occur on the articles within the space provided therefore.

Further, it is one of the prime features of the present invention to slidably mount an assemblage including a refrigerant compressor, motor for driving the compressor and a coil, whereby the entire unit may be removed from the housing in order to service the same.

Referring now primarily to Figure 1 one form of the invention is illustrated in detail. Here a conventional floor 10 is illustrated with the usual structure associated therewith and a housing 12 is rested thereon. This housing is preferably of a decorative material and preferably one having insulating qualities of merit. A liner 14 is supplied within the said housing and a conventional vision glass 16 is associated therewith. The usual doors 18 are associated with the back portion of the said housing 12 for lending access to the interior thereof.

A substantially U-shaped baffle 20 is secured within the said housing 10 by any suitable means, preferably by utility of the angle rails indicated at 22. This substantially U-shaped baffle has legs with sets of louvers 24 and 26 respectively. The said louvers 26 open downwardly, while the said set of louvers 24 are opened in the same direction. However, due to the normal passage of air as indicated by the arrows in Figure 1, the louvers are oppositely facing relative to the direction of air flow. It will be noted that the upper portion of the said housing is unobstructed thereby permitting free flow of air passage over the top portion of the display compartment immediately behind the said vision window 16.

A partition 28 is secured to the bottom 30 of the said housing and the said partition has a platform 32 secured thereto. An opposite end of the said platform 32 is secured to the liner, thence the housing by being operatively associated with the bearing block 34, which is secured directly to the liner and housing. Preferably beneath the said bearing block 34 there is supplied an aper-

ture 36 which may have a filtering screen 38 positioned therein.

A drip pan or tray 40 having a down curved spout portion 42 rests on the said platform 32 and has a conventional cooling coil 44 seated thereon. Of course, if it is found desirable the said cooling coil 44 may rest directly upon the drip pan or tray 40 or may be spaced therefrom by means of small legs or blocks 46. As is well known, the cooling coil 44 precipitates liquid or moisture from the air which drips onto the pan 40. This condensation is directed over the spout 42 and impinges upon a frame 48 which has absorbent material 50 extending thereacross. This material may be of any conventional description such as wick material, wadding between a pair of screens or others.

The frame including the wick or other absorbent material is utilized as a humidifier for the interior of the housing 12.

Referring now to Figure 5 it will be seen that a pan 52 is supplied wherein the said wick bearing frame 48 is seated. This frame may be secured to conventional arcuate brackets 54 and 56 respectively by means of conventional lugs 58 extending from each side of the said frame 48. The lugs are then received in the arcuate slots formed in the said brackets 54 and 56 and a conventional wing nut 60 may be associated with each lug 58. Of course, the entire frame 48 may be lifted from the interior of the pan 52 to a position as illustrated in fantom in Figure 2, exterior of the said pan. In order to anchor the said brackets 54 and 56 respectively any suitable means may be utilized such as securing them firmly to the sides of the said pan 52.

In order to maintain a supply of liquid within the said pan 52, a drain line or tube 62 is secured thereto and communicates with the upper portion of the said pan 52. By this medium a constant supply of liquid may be maintained in the pan 52 and the overflow drained therefrom. The said tube 62 may obviously extend through the base or bottom of the said housing 12, then through the floor construction 10.

The entire coil including its appurtenant compressor 64, conventional motor 66 and other appurtenances contiguous thereto may be readily attached and detached within the said housing 12. The said partition 28 cooperating with the said platform 32 forms a zone which is known as the case wherein a shelf or platform is slidably received. It is readily appreciated from inspection of Figure 1 that conventional tubing or other similar lines 72 and 74 respectively extend through the inlet and outlet side of the coil 44. These tubes are operatively connected with the appurtenances contiguous to compressing and pumping coolant.

Rails 78 and 80 are positioned on the said bottom or base 30 and secured thereto by any suitable means. Substantially U-shaped brackets or rails 82 and 84 respectively are rigidly secured to the said shelf or platform 70 for cooperation with the said rails 78 and 80. By this means the entire shelf or platform 70 may be slidably received in the said case and maintained in position until it is desired that the entire assemblage or unit should be removed. In order to firmly maintain the shelf or platform 70 within the case, conventional brackets 86 and 88 may be rigidly secured in the said bottom or base 30 for overlying the marginal edges of the said platform.

Means for impelling air within the housing is provided. The preferable means may be seen as

a conventional fan generally indicated at 88 which is positioned in an aperture 89. The said aperture 89 is of course formed in a suitable partition 90 (see Figure 10) which fits firmly against the angle support 22 and the base or bottom 30. The specific fan mounting means comprises a pair of conventional brackets 92 and 94 respectively. It is noted that these brackets may be substituted by other conventional mountings if it is found desirable.

The fan of course urges air over the cooling unit 44 and it will be noted at this point that the platform or shelf 32 cooperating with the lower portion of the said U-shaped baffle 20 defines a restricted air passage for directing a rapid flow over the coils 44. Of course, the air is circulated through the passages defined by the legs of the said substantially U-shaped baffle and the sides of the housing 12 and over the upper portion of the display compartment as described above.

Referring now to Figure 7 it will be seen that a modified form of the invention is disclosed. This modified form includes a shut off plate 96 which covers the said aperture 89. A conventional manually adjustable louver construction 98 is associated therewith for controlling the amount of air flowing through the device. Of course, a conventional thermostat and/or humidostat may be utilized for actuating a slightly different type of louver construction 98, if it is found desirable.

Having described the invention, what is claimed as new is:

1. A cooler comprising a housing, a partition in said housing, a shelf secured to said partition forming a case thereunder, a platform, means for slidably securing said platform in said case, means secured to said platform and slidable therewith for compressing and circulating refrigerant, a coil connected with said compressing means, a tray seated on said shelf beneath said coil supporting said coil, a drip pan in the housing adjacent said case, a drain secured to said pan, and absorbent means mounted for adjustable movement in said pan.

2. A cooler comprising a housing, a partition in said housing, a shelf secured to said partition forming a case thereunder, a platform, means for slidably securing said platform in said case, means secured to said platform and slidable therewith for compressing and circulating refrigerant, a coil connected with said compressing means, a tray seated on said shelf beneath said coil supporting said coil, a drip pan in the housing adjacent said case, a drain secured to said pan, absorbent means mounted for adjustable movement in said pan, and means for locking said absorbent means in selected positions within said tray beneath the outlet of said drip pan and exterior of said drip pan.

3. A cooler comprising a housing, a partition in said housing, a shelf secured to said partition forming a case thereunder, a platform, means for slidably securing said platform in said case, means secured to said platform and slidable therewith for compressing and circulating refrigerant, a coil connected with said compressing means, a tray seated on said shelf beneath said coil supporting said coil, a drip pan in the housing adjacent said case, a drain secured to said pan, absorbent means swingingly secured to said pan, means for locking said absorbent means in selected positions within said tray beneath the outlet of said drip pan and exterior of said drip

pan, and air impelling means secured in said housing adjacent said absorbent means.

4. A cooler comprising a housing, a partition in said housing, a shelf secured to said partition forming a case thereunder, a platform, means for slidably securing said platform in said case, means secured to said platform and slidably therewith for compressing and circulating refrigerant, a coil connected with said compressing means, a tray seated on said shelf beneath said coil supporting said coil, a drip pan in the housing adjacent said case, a drain secured to said pan, absorbent means swingingly secured to said pan, means for locking said absorbent means in selected positions within said tray beneath the outlet of said drip pan and exterior of said drip pan, air impelling means secured in said housing adjacent said absorbent means, a substantially U-shaped baffle forming a display compartment secured in said housing, said baffle being spaced from said shelf to form an air passage having said coil therein, said U-shaped baffle having legs spaced from the walls of said housing, sets of oppositely inclined louvers in said legs and the legs terminating adjacent but spaced from the top of the display compartment to form an unobstructed passage for air over the compartment.

5. A cooler comprising a housing, a partition in said housing, a shelf secured to said partition forming a case thereunder, a platform, means for slidably securing said platform in said case, means secured to said platform and slidably therewith for compressing and circulating refrigerant, a coil connected with said compressing means, a tray seated on said shelf beneath said coil supporting said coil, a drip pan in the housing adjacent said case, a drain secured to said pan, absorbent means swingingly secured to said

pan, means for locking said absorbent means in selected positions within said tray beneath the outlet of said drip pan and exterior of said drip pan, air impelling means secured in said housing adjacent said absorbent means, a substantially U-shaped baffle forming a display compartment secured in said housing, said baffle being spaced from said shelf to form an air passage having said coil therein, said U-shaped baffle having legs spaced from the walls of said housing, sets of oppositely inclined louvers in said legs and the legs terminating adjacent but spaced from the top of the display compartment to form an unobstructed passage for air over the compartment.

6. The combination of claim 5 and air flow control means operatively connected with said air impeller means.

JOSEPH JOHN SCHMIDT.
LOUIS L. POPKY.
